UNITED STATES PATENT OFFICE

2,461,633

RESILIENT CONNECTION FOR BRAKE RODS
AND THE LIKE

George B. Dorey, Westmount, Quebec, Canada

Application March 17, 1945, Serial No. 583,349

4 Claims. (Cl. 267—72)

1

My invention relates to an improved type of resilient connection for incorporation in the brake rigging of railway cars and the like and is by way of an improvement on my United States Patent No. 2,106,343 of January 25, 1938.

An object of my invention is to provide a resilient extensible connection wherein the parts are maintained in a definite spaced relation to each other at all times so as to prevent interference between the relatively movable parts as the connection is extended.

A particular object of my invention is to provide a structure having a pair of clevis members in combination with an interlocking spacing washer to maintain the pair of jaws constituting the clevis in spaced relation.

My invention further resides in certain details of construction such as will be fully pointed out hereinafter and claimed.

For further comprehension of my invention reference may be had to the accompanying drawings wherein:

Figure 1 is a vertical elevational view of my improved resilient connection showing the structure in assembled relation with the central rod cut away.

Figure 2 is a vertical side elevational view of the assembly shown in Figure 1 as viewed from right to left.

Figure 3 is a top plan view of Fig. 1 showing the rod in section and as viewed on a line 3—3 of Fig. 1.

Figure 4 is a vertical elevational view of one of the clevis pieces shown in Figure 2.

Figure 5 is a side view of the clevis piece shown in Figure 4.

Figure 6 is a top plan view of Figure 5.

Figure 7 is a plan view of the washer shown in Fig. 3.

Figure 8 is a side view of the washer shown in Figure 7 as viewed from right to left.

Fig. 9 is a perspective view of the centrally disposed shouldered rod.

Referring now to the drawing, A indicates a centrally disposed shouldered rod movable in one direction and B indicates a yoke structure movable in the opposite direction from the central rod; said yoke structure includes a pair of clevis pieces C—C, a washer D interlocked with the clevis pieces and a separator E interposed between the pair of clevis pieces and secured thereto by a rivet F. Interposed between the shoulder of the central rod and the washer D is a coil spring G.

The centrally disposed shouldered member A

2

is preferably formed from a round rod 10 which extends lengthwise of the connection and is formed with an enlarged head portion 11, said head portion lies within the spring and outwardly of the spring is formed with a T shaped shouldered head 12; said shoulder being engageable with one end of the spring. The rod is movable in a direction as indicated by the arrow 13 on compression of the spring. The enlarged head portion 11 is formed with curved side walls 14 to conform to the curved inner surface 15 of the inside face of the coil spring and the body portion of said head is preferably of I section defined by web 16 and side walls 17.

The body portion of the head at an appreciable distance from the shoulder is formed on each side with a flat bearing surface 18, said surfaces constituting bearing walls which act to guide the central member between the inner bearing surfaces of the jaw pieces.

Disposed at the sides of the central member are the clevis pieces C—C. Each clevis piece includes a shank portion 19 lying within the spring G, said shank portion having an outer curved surface 20 corresponding to the inner face of the spring and an inner flat wall 21, said last named wall constituting a guiding wall for one of the bearing surface 18 of the central member. Each clevis member is provided with a shouldered portion 22 projecting outwardly beyond the shank and laterally to the sides to provide projecting end portions 23. The end walls of the projecting portions 23 are indicated at 24 and extend substantially radially from the axial center of the spring on lines as indicated at 25. The shouldered portion 22 is tapered slightly to present an inclined bearing surface on its lower face as indicated at 26.

Each clevis member on the end opposite to the shouldered portion is extended lengthwise beyond the spring and there formed with an enlarged portion 27 whereby the pair of spaced members present a clevis like structure having transversely aligned openings indicated at 28 and 29 respectively. The respective clevis portions are spaced apart a sufficient distance to accommodate a lever or other suitable member between the jaws of the connection and the parts are maintained in such spaced relation by suitable spacing means as will be described hereinafter.

The spacing means at one end of the spring consist of the separator E which is maintained in place by the rivet F and the spacing means at the opposite end is carried out by the washer D.

through its interlocking relation with the shouldered portions of the clevis pieces.

Said washer D includes a flat ring shaped body portion 30 having a circular opening 31 corresponding substantially to the shape of the inside of the spring. The under surface 32 of the body of the washer consists of a flat surface which bears on the end of the spring. Extending outwardly from the body portion of the washer are projecting walls 33 each having end walls 34 extending in a substantially radial direction from the axial center of the spring on lines indicated at 35. The body portion of the washer on its upper surface presents seats 36 for receiving the shouldered portions of the clevis pieces. Said seats 36 incline radially at a slight angle towards the center of the washer, said inclination corresponding substantially to the inclination formed by the tapered bearing portion of the clevis shoulder which has the inclined surface 26. The seats 36 in combination with the end walls 34 thus present pockets in which the shouldered portions of the clevis pieces are received and held in interlocked relation. The fact that the bearing seats 36 incline towards each other has the effect of forcing the respective clevis pieces inwardly towards each other thus causing the end walls 24 of the clevis pieces to bear against the radially extending walls 34 of the washer. The interlocking relation between the clevis pieces and the washer thus maintains the shanks of the jaw pieces against lateral or sideways displacement and outward movement of said shanks is further prevented by reason of the fact that the ring shaped body portion of the washer encircles the shanks of the clevis pieces.

The inner face of the ring shaped washer lies immediately adjacent to the outer curved surface of the shanks of the clevis pieces and this further serves to center the washer in relation to the coil spring. The combination of the pair of clevis pieces and the associated spacing means adjacent the opposite ends of the spring provides a yoke structure having the rigidity of an integral member and assures through the medium of the washer for an even bearing on the end of the spring. The coil spring is placed under initial compression when the parts are assembled and thus all the parts of the connection are firmly held in position. The enlarged clevis portions 21 which lie beyond the spring are generally formed of greater width than the inside diameter of the spring and consequently when assembling the device it is necessary that the clevis members be individually threaded through the spring. In order to permit of assembly the shouldered ends 22 of the clevis pieces are so formed and proportioned as to readily pass through the spring and ring shaped washer.

With the yoke structure in assembled relation it will be seen that the inner flat faces 21 of the pair of clevis pieces present parallel guiding walls between which the central rod is contained and guided. The flat bearing surfaces 18 on the central rod provide for adequate support in the event that the connection is used in a horizontal position.

While I have shown a preferred embodiment of my invention it will be understood that the same is merely illustrative and I contemplate all modifications coming within the scope of the appended claims.

What I claim is:

1. A resilient extensible connection comprising oppositely movable shouldered means and a

coil spring interposed between the shoulders of the respective movable means; one of said shouldered means consisting of a centrally disposed member extending through the spring and the other of said shouldered means being in the form of a yoke assembly including a pair of clevis members and a washer; said pair of clevis members being spaced apart to accommodate the central member therebetween and said washer being interlocked with the clevis members to maintain said pair of clevis members in spaced relation, said washer including a ring shaped body portion seating on the spring and oppositely disposed notches formed in said ring to present end wall abutments and a seat between said abutments, said clevis members presenting laterally extending shoulders formed with end walls arranged to register with the end walls of the notches, each said shoulder having a seating surface extending between the end walls for seating upon the seat of the associated notch.

2. A resilient extensible connection comprising oppositely disposed shouldered means movable relatively to each other and a coil spring interposed between the shoulders of the respective means; one of said shouldered means including a pair of shouldered clevis members spaced apart and the other of said shouldered means including a centrally disposed member extending between the pair of clevis members; and a washer interposed between the shoulders of the clevis members and the adjacent end of the spring, said washer having abutments associated therewith engaging with the shouldered portion of the clevis members to maintain said pair of members in spaced relation, said abutments of the washer presenting walls extending lengthwise of the connection and angularly related to present outwardly flaring V arranged end walls forming notches for the accommodation of the shoulder of the clevis therein, said shouldered portions of the respective clevis members being formed with outwardly V arranged end walls for engagement with the end walls of the notches of the washer.

3. As an article of manufacture, a resilient extensible connection including oppositely disposed relatively movable shouldered members and a coil spring interposed between the shoulders of the respective members; one of said members extending centrally through the spring and the other of said members including a pair of shouldered clevis members each disposed on opposite sides of the central member; and a washer having a body portion interposed between the shoulders of the clevis members and one end of the spring, said washer having abutments outstanding from the body portion, said abutments extending substantially radially relatively to the axial center of the spring, and abutments on the shoulders of the clevis members engaging with the first named abutments, said co-operating abutments operating to maintain the clevis members in definite spaced relation.

4. As an article of manufacture, a resilient extensible connection including a coil spring and oppositely movable shouldered elements embracing the opposite ends of said spring; one of said elements extending centrally through the spring and the other of said elements being in the form of a yoke assembly including a pair of shouldered clevis pieces and a bearing washer, said clevis pieces being positioned on the respective sides of the centrally extending element, each said clevis piece having a shank portion presenting

an outer surface concentrically formed to correspond with the inner face of the spring and having a flat inner face constituting a guiding wall for the centrally extending member; said bearing washer having a ring shaped body portion encircling the shank portions of the pair of clevis pieces, said body portion of the washer being interposed between the shoulders of the clevis pieces and the adjacent end of the spring, said washer having seats for receiving the shoulders of said clevis pieces and abutments at each end of the seats outstanding from the body portion of the washer, said abutments extending between the pair of clevis pieces to maintain the same in definite spaced relation, said shoulder receiving seats on the washer being slightly inclined downwardly towards the abutments to maintain the clevis pieces in engagement with the abutments when longitudinally acting tensional pressure is applied on the connection.
